UNITED STATES PATENT OFFICE.

ALBEN E. LUNDELL, OF NEW YORK, N. Y., ASSIGNOR TO WESTERN ELECTRIC COMPANY,
INCORPORATED, OF NEW YORK, N. Y., A CORPORATION OF NEW YORK.

TELEPHONE-EXCHANGE SYSTEM.

1,271,335.

Specification of Letters Patent.

Patented July 2, 1918.

Application filed January 11, 1916. Serial No. 71,540.

To all whom it may concern:

Be it known that I, ALBEN E. LUNDELL, a citizen of the United States, residing at New York, in the county of Bronx and State of New York, have invented certain new and useful Improvements in Telephone-Exchange Systems, of which the following is a full, clear, concise, and exact description.

This invention relates to telephone systems, and more particularly to improvements in busy test circuits as employed on telephone switchboards.

The principal object of this invention is to provide means whereby a busy test indication will be effective only with the receiver of an operator's telephone set; and not effective with a telephone circuit connected in proper talking relation with the operator's set. Another object of this invention 20 is the provision of a telephone system wherein one party may ascertain whether the telephone of a second party is in use or not without giving any indication thereof to a third party, whose telephone is in talking 25 relationship with the telephone of the first party.

In accordance with one embodiment of this invention, a trunk circuit operator's telephone set is equipped with a plurality of 30 current transformers of an inductive type. The current encountered when a busy test operation is applied to a subscriber's line circuit on which a connection is present acts on one of transformers to induce a current 35 in the telephone receiver of the operator applying the test. The same current also acts on another one of the transformers to neutralize the induced busy test currents with respect to that portion of the operator's 40 set to which an exterior telephone circuit is adapted to be connected.

More specifically, this invention embodies 45 separated switchboards or telephone central offices between which connections are completed by means of trunk circuits. At a trunk operator's position each trunk circuit terminates in a cord and plug, and is provided with a listening key, and a signal adapted to be operated when a call originates 50 at the sending end of a trunk circuit. A call is answered by means of the listening key associated with the trunk on which a call is present, and on an order being received thereover, the trunk circuit operator 55 tests the line circuit of the subscriber wanted

by touching the tip of the trunk plug to the shell of the subscriber's line jack which is a well-known operation. During the time the operator is applying this busy test, the listening key may remain in the talking position with respect to the operator's set and the trunk circuit, and this invention provides that in case a busy condition is encountered on the line tested, the characteristic busy signal indication will only be manifested in the operator's telephone receiver and not on the trunk circuit.

This invention is illustrated diagrammatically in the accompanying drawing, in which is shown only such portions of a telephone exchange equipment as will be necessary in describing the features of this busy test system. The reference numeral 1 indicates a subscriber's line circuit terminating in a multiple type central energy switchboard, and another similarly equipped subscriber's line terminating in another switchboard is indicated at 2. At the first switchboard a link circuit 3 is employed for completing telephone connections, and a trunk 75 circuit 4 extends from the first to the second switchboard. An operator's telephone set 5 at the receiving end of the trunk circuit 4 is equipped in a manner suitable for practising the features of this invention.

Referring to the drawing, the operation of this system will be apparent from a description of the steps necessary in the handling of a call originating at the station 1 in which it is desired to secure a connection 90 with the station 2.

This call is first manifested on a line signal 6, whereupon an operator inserts a plug 7 of the link circuit 3 into a jack 8 of the line circuit 1. By means of an operator's telephone set (not shown) the operator talks with the calling party at the station 1, and on receiving a request for connection with the subscriber 2 inserts a plug 9 of the link circuit 3 into a jack 10 of the trunk circuit 4. 100 Battery current to the link circuit 3 operates a relay 11 at the distant end of the trunk circuit, thereby lighting a signal lamp 12. In response to this signal, an operator at 5 sets a listening key 13 and talks either with 105 the originating operator at 3 or with the subscriber at station 1 (it will be understood that a transmitter, not shown, is associated with the operator's telephone set at 5), and in this case receives a request for connection 110

with the station 2. In order to determine the idle or busy condition of the line 2, the trunk operator momentarily touches the tip of a trunk plug 14 to the shell of a jack 15 of the line 2, and if no click is heard in a telephone receiver 31, the plug 14 is inserted in this jack. The relay 17 now operates over the signal circuit conductors of this connection in series with the cut-off relay 18 of the line circuit 2. A contact member 19 of the relay 17 disconnects the path to earth, over which the lamp 12 was first lighted, and connects a resistance unit 20 to complete a circuit through the contacts of the relay 11, whereby the lamp 12 is shunted and accordingly extinguished. A contact member 20' of the relay 17 disconnects the tip conductor of the trunk circuit plug 14 from the primary windings 23 and 24 of two transformers 21 and 22, respectively, and completes the continuity of the tip conductor of the trunk circuit 4. Although not shown, it will be understood that a suitable source of ringing current is present with the link circuit portion of the trunk 4 for operating a call signal at the station 2.

Let it now be assumed that the call just considered, instead of finding the line 2 idle, meets a busy condition of this line circuit. A busy condition of the line 2 may, for convenience, be considered as present on the insertion of a plug 29 in a jack 30, which is common to this line. Although complete circuits are not shown for the plug 29, it will be understood that these circuits may be considered as extending to a trunk circuit similar to 4, or a link circuit similar to 3, suitable for completing a telephone connection between two subscribers' lines. Under this condition, when the call from station 1 reaches the operator at 5, and this operator touches the tip of the plug 14 to the shell of the jack 15 in making the necessary busy test of the line 2, current from a grounded battery connected to the signal circuit conductor of the plug 29 will flow over the tip circuit of the plug 14, the normal contact of the member 20' of relay 17, and the primary windings 23 and 24 of the transformers 21 and 22, respectively, to earth. Although this impulse of busy test current through the primary windings 23 and 24 of the transformers induces a corresponding impulse of current in each of the secondary windings 25 and 26 of the transformers, the latter windings are connected in series in such relation one with the other that the current polarity sign induced in one coil presents an opposing current polarity sign to the current induced in the other coil. The two transformers are exactly balanced as to current reproduction; therefore the inductive effect of the transformers neutralize with respect to the serially connected windings 25 and 26, which are in turn included by means of the listen-

ing key 13 in bridge on the main conductors of the trunk circuit 4. Accordingly induced current impulses through the windings 25 and 26 of the transformers 21 and 22 respectively, do not produce current action in the main conductors of the trunk circuit.

The manner in which busy test impulses are manifested in the operator's telephone receiver 31 may be described as follows: It will be noted that the telephone receiver 31 is connected in series with a condenser 28 and that this series circuit is included in bridge on the secondary winding 26 of the transformer 22; therefore the receiver 31 is included in a closed circuit formed through the transformer winding 26 independently of the secondary winding 25 of the other transformer 21. Currents induced by the winding 24 in the secondary winding 26 of the transformer 22, circulate freely through the telephone receiver 31, which action takes place when busy test current is encountered on a subscriber's line circuit as described.

A resistance unit 27 connected in bridge on the secondary winding 25 of the transformer 21, serves to eliminate the effective or impedance resistance effect of the winding 25 in completing a series circuit, whereby the telephone receiver 31 is included by means of the listening key 13 in bridge on the main conductors of the trunk circuit 4 for the purpose of holding telephone communication thereover. The resistance unit 27 also serves to maintain a symmetrical current condition with respect to the secondary windings 25 and 26 of the transformers 21 and 22, by consuming an amount of current induced in the coil 25 approximately equal to the current consumed by the circuit of the receiver 31, which current is that induced in the coil 26.

From the foregoing description it will be apparent that although currents induced by a busy test operation may be heard in the telephone receiver 31 during the time this receiver is connected to the main conductors of the trunk circuit 4, no current effect from such busy test indication will however, be present on the trunk circuit.

It will be understood that the subscriber's line 1 may terminate in an automatic exchange, in which case, suitable selector switch equipment would be employed in connecting the subscriber's line 1 with the trunk circuit 4, and accordingly the manually operated link circuit 3 and the jacks associated with the line circuit 1 and the trunk circuit 4 dispensed with.

The relays and signal lamps associated with the link circuit 3 are of a well-known supervisory type and therefore do not require to be further described. A supervisory relay 32 on the trunk circuit 4 also operates in a well-known way, and the lamp 12 in addition to acting as a call signal also serves as a disconnect signal on a connected trunk.

This disconnect signal being effective on the disconnection of the shunting resistance 20 on the release of the relay 11 which takes place when the link plug 9 is removed from 5 the jack 10 of the trunk circuit 4.

What is claimed is:—

1. In a telephone exchange system, a telephone line, an operator's telephone circuit including a receiver, switching means for 10 including said operator's receiver in circuit with said line, a busy test circuit, and means in said circuit for rendering it effective with respect to the telephone receiver but ineffective with respect to the line with which 15 said telephone receiver may be connected.

2. In a telephone exchange system, a telephone line, an operator's telephone circuit including a receiver, switching means for including said operator's receiver in circuit 20 with said line, a busy test circuit, and current transforming means for rendering the current through said busy test circuit effective with respect to the operator's receiver and neutralizing the current with respect to 25 the line with which said receiver may be connected.

3. In a telephone exchange system, a subscriber's line, an operator's circuit including a receiver, switching means for connecting 30 said receiver with said telephone line, a busy test circuit including a source of energy, current transforming means in said busy test circuit for inducing a current in said telephone receiver, and a second current transforming means in said busy test circuit for 35 producing a current flow equal to that through said first transforming means but in the opposite direction, said second transforming means being connected in the circuit

of said operator's receiver and the line to 40 prevent the flow of current from said first transforming means over said line.

4. In a telephone exchange system, a subscriber's line, an operator's circuit including a receiver, switching means for connecting 45 said receiver with said subscriber's line, a busy test circuit, a current transforming means having its primary in said busy test circuit and its secondary in multiple with said operator's receiver, and a second transforming means having its primary in the 50 said busy test circuit and its secondary in a portion of the circuit between said receiver and said line circuit, the flow of current through the secondary of said second transformer being equal and opposite to the flow of current through the secondary of the first mentioned transformer whereby the current flow through said first mentioned transformer will be neutralized with respect to the 55 line with which the operator's telephone is connected.

5. In a telephone system, a telephone line, a telephone receiver connected thereto, a busy test circuit, means included in said busy 65 test circuit to render it effective with respect to said telephone receiver but ineffective with respect to said telephone line.

6. In a telephone system, a link circuit, a telephone receiver connected thereto, a busy 70 test circuit, and means included in said busy test circuit to render it effective with respect to said telephone receiver but ineffective with respect to said link circuit.

In witness whereof, I hereunto subscribe 75 my name this 10th day of January A. D., 1916.

ALBEN E. LUNDELL.
